UNITED STATES PATENT OFFICE.

HARRY G. HALL, OF ATLANTA, GEORGIA.

COLLAPSIBLE BOX.

1,271,034.

Specification of Letters Patent.

Patented July 2, 1918.

Application filed July 21, 1916, Serial No. 110,508. Renewed December 5, 1917. Serial No. 205,684.

To all whom it may concern:

Be it known that I, HARRY G. HALL, a citizen of the United States, residing at Atlanta, in the county of Fulton and State of Georgia, have invented new and useful Improvements in Collapsible Boxes, of which the following is a specification.

This invention generically relates to boxes of the pasteboard type constructed from a one piece blank, but it more especially comprehends that style termed foldable, knock-down or collapsible; and one object is to provide a box which can be quickly and economically constructed; will fold flatly, and be capable of utilization for various purposes in the art.

Another object is to provide a box which may be constructed from a single blank and expeditiously changed from erected to collapsed position, or vice-versa.

A further object is to provide a box having reinforced and rigidly stayed corners, capable of withstanding rough and continued usage, and when filled will not disengage at the corners, a defect prevalent in boxes of this character.

Other and still further objects are to provide a box which, though easily collapsed or erected, may be durable, efficient, and comprising few parts or sections.

With these and other objects in view my invention consists in certain novel details of construction, combination and arrangement of parts to be more particularly hereinafter set forth and claimed.

In the accompanying drawings, in which corresponding parts are indicated by similar reference characters:

Figure 1 is a top plan view of the blank cut and scored, and prior to folding;

Fig. 2 is a similar view to that of Fig. 1, with sides 2 in folded position;

Fig. 3 is a similar view to that of Fig. 2, showing end reinforcing flaps 5 in position, ends folded, and showing the entire blank in collapsed position;

Fig. 4 is a fragmentary perspective view, showing folded flap in position, and ends in course of erection;

Fig. 5 is a similar view to that of Fig. 4, one step nearer complete erection; and

Fig. 6 is a similar view to that of Fig. 5, with end completely erected, and with end extension flaps 5^b in locked position.

In the illustrated embodiment characterizing my invention, Fig. 1 illustrates a blank substantially rectangular in shape and comprising a bottom section 1 bounded by score lines 1^a, extending lengthwise from end to end at a distance from the outer edge of the blank equal to the desired depth of the box, and transversely extending score lines 1^b parallel with the ends of the blank, and at a distance therefrom equal to twice the desired depth of the box. By the score lines 1^a are formed side sections 2, carrying near their upper and outer corners tongues 2^a formed by cutting along lines 2^b.

The extension of score lines 1^a and 1^b beyond their intersection constitutes score lines 4^b and 2^c, respectively, and forming corner sections 3. Said corner sections 3 are scored diagonally along line 3^a from their innermost corners 3^a to their outermost corners 3^c, tapering slightly from the outer end of score line 2^c to the corner 3^c along the line 3^d, and from the end of score line 4^a to the outermost corner 3^c along the line 3^e. The corner sections 3 are creased along score lines 3^a and constitute inwardly folding corner staying reinforcing and connecting members.

By the score lines 1^b are formed sections 4 constituting the ends of the box. Equidistant from score line 1^b and the end of the blank is the parallelly extending score line 4^a effecting inwardly foldable end reinforcing and staying flap 5. Said flap 5 is provided with the score line 5^a, defining the locking extension and corner staying members 5^b. At each end of score line 4^a are provided the substantially V shaped cuts or notches 6, which not only form the inner walls of extension members 5^b, but also gives the proper taper to corner sections 3 along the line 3^e.

To properly guide the folding upon itself of the inwardly folding section 3, the staple

7 or other suitable fastening elements are provided, securing the outer fold 3^t of the corner section 3 to the end section 4. In order to facilitate the erection as well as the 5 collapsing of the box, fastening elements 8 are provided, securing to end section 4 the end folding and reinforcing flap 5.

The facility with which a box may be constructed from a single blank, according to 10 my invention, as above outlined, is at once apparent. The pattern as clearly shown in Fig. 1, can be easily and quickly cut, and owing to the few necessary score lines, the entire preparation preparatory to putting 15 the blank in condition for setting up as a completed box requires but a minimum expenditure of time and labor.

After the blank has been prepared, as 20 shown in Fig. 1, the sides are folded on scores 1^a and staples or other suitable fastening elements are inserted to secure the outer fold 3^t of corner section 3 to end section 4, as clearly shown in Fig. 2 of the drawing. The end flaps 5 are then folded 25 over and inwardly on end sections 4, on scores 4^a and secured thereto by staples 8 or other suitable fastening elements, as clearly shown in Fig. 3.

The box is then in collapsed position, and 30 it will be observed that when thus folded it practically consists of a rectangular sheet, occupying but little space, and may be stacked one above the other facilitating shipping, storing and handling. If desired, the 35 extension members 5^b may be folded downwardly and inwardly on scores 5 between end flaps 5 and side sections 2, in which event a perfect rectangular sheet will be obtained.

40 To place the box in erected position it is but necessary to raise the side sections 2, the first step of which is shown in Fig. 4, to perpendicular position, and as the outer fold 3^t of the corner section 3 is secured to the 45 end 4, the raising of the side sections 2 causes corner sections 3, as shown in Figs. 4 and 5, to fold, at the same time drawing up end sections 4 to perpendicular position, and as the reinforcing folded over end flap 5 is secured to end section 4, as it comes to 50 perpendicular position, will be caused to slide over the inwardly extending corner staying flaps formed by the folding of corner sections 3 upon themselves.

55 Thus, it is obvious that by the simple and single operation of raising side sections 2, every part of the box is brought to its proper erected position, and the only further operation necessary is to place the extension and 60 staying flaps 5^b under the locking tongues 2^a, when the box will be in completely erected position, ready for use, as clearly shown in Fig. 6 of the drawing.

A cover may be provided by following the

same construction as that of the box, but 65 sufficiently dimensioned to telescope the said box.

Many efforts have been made, but with scant success, to provide a box of this type which would withstand hard usage, be collapsible, yet sufficiently tight to prevent the escape of liquid matter. 70

Particular attention is directed to the corner construction, in that, I have provided a number of folds so arranged as to form two 75 exterior and one interior corner, each independent of the other. After the exterior corners have succumbed to wear or become otherwise damaged, the interior or auxiliary corners formed by the extension and locking flaps 5^b will be left intact, and the usefulness of the box will still be unimpaired. 80

By this construction it will be readily seen that the life of the box is doubled in addition to being far more durable and substantial than those now in use. Not only do the locking flaps 5^b provide auxiliary corners, but they also constitute stays, lending rigidity and stability to the ends of the box, at the same time performing a similar function with respect to the sides. Also these extension flaps 5^b perform still another important function in constituting locking members capable of firmly holding in position the end sections of the box, when properly adjusted under the locking tongues 2^a. 90

Another novel feature relative to the corner construction is the corner staying and connecting sections 3^a, which, when the box is in erected position, constitute inwardly 100 projecting extension stays of a thickness twice that of the sides and being positioned interjacent the end section 4 and end reinforcing flap 5, not only further stiffen the ends, but absolutely prevent the sides from 105 being forced apart at the corners, irrespective of the force or weight outwardly directed against them.

It will be observed that in constructing the corners in accordance with my invention 110 there are no slits or notches, and when the box is in erected position a continuous and unbroken side and end wall is provided constituting a non-leakable box.

It is apparent that the locking members 115 5^b, end reinforcing flaps 5, end sections 4, and sides 2, all perform with respect to the corners double functions, thereby producing a corner construction for boxes of this character superior to those now known to the art. 120

Having now described my invention, what I claim is:—

In a box member, the combination of end and side sections in folded relation at the corners, inturned staying flaps on the end sections, locking members coextensive with the lateral edges of said staying flaps and projecting inwardly in parallelism and ad-

acent the inner surfaces of the side sections, effecting a double ply of material contiguous the extremities of said side sections, and producing a reinforcing corner interior of 5 the corner folds, and tongues on said side sections adapted to engage the upper edges of said locking members, constituting in con-

nection therewith a lock, substantially as and for the purpose set forth.

HARRY G. HALL.
